United States Patent Office.

CHARLES WEBER AND HENRY REIMANN, OF WEST MERIDEN, CONNECTICUT.

Letters Patent No. 82,458, dated September 22, 1868.

IMPROVEMENT IN LAMPS.

The Schedule referred to in these Letters Patent and making part of the same.

TO ALL WHOM IT MAY CONCERN:

Be it known that we, CHARLES WEBER and HENRY REIMANN, both of West Meriden, in the county of New Haven, in the State of Connecticut, have invented a new and useful Improvement in Lamps; and we do hereby declare the following to be a full, clear, and exact description thereof, which will enable those skilled in the art to make and use the same, reference being had to the accompanying drawing, forming part of this specification, in which drawing—

Figure 1 represents a vertical central section of this invention, the plane of section being indicated by the line $x\ x$, fig. 3.

Figure 2 is a similar section thereof, taken in the plane indicated by the line $y\ y$, fig. 3.

Figure 3 is a horizontal section of the same, the line $z\ z$, fig. 1, indicating the plane of section.

Similar letters indicate corresponding parts.

This invention consists in the arrangement of a cup in the neck of the oil-cistern, in such a manner that the oil resulting from the condensation of unconsumed vapors will collect in said cup, and thus the oil-cistern will remain clean, and free from the oil generally collecting thereon.

The invention consists, further, in the arrangement of a ring or open platform, for supporting the chimney or cylinder below the sieve which admits air to the interior of the cone and burner, in such a manner that a powerful and uniform current of air passes to the flame, inside and outside of the cone, and thereby a perfect combustion of the oil is insured.

The invention consists, finally, in the arrangement of inwardly-projecting lips on the ends of the slot in the cone, in such a manner that the current of air passing up from below is caused to impinge against said lips, and thereby the brilliancy and force of the flame are materially increased.

A represents the oil-cistern of our lamp, which is made of glass, or any other suitable material. In the neck of this oil-cistern is secured a cup, B, which may either be made solid with the cistern, or connected to the same by cement or any other suitable means. This cup surrounds the lower part of the wick-tube C, which is secured in the screw-thimble D. This thimble screws into the neck of the oil-cistern in the ordinary manner, and it is provided with one or more recesses, α , (see fig. 2,) which form channels, extending from the cup B down into the cistern, so that the oil collecting in the cup finds its way down into said cistern.

The upper part of the thimble D forms a chamber, in which are situated the feed-wheels b , and over the thimble is fitted a sleeve, c , which supports the burner. Said sleeve is provided with one or more projecting lips, corresponding in number and position to the recesses α , in the thimble D, so that when the sleeve is depressed, said lips will close the recesses, and cut off the communication between the oil-cistern and the external atmosphere, but when the sleeve is raised, the recesses α are opened, and the cistern can be supplied with oil without removing the thimble.

The burner consists of the open platform E, the air-sieve F, and the cone G. The platform E is situated below the air-sieve, and it serves to support the glass cylinder H, which is held in position by a series of elastic fingers, d , rising from the platform, and bearing against the inner surface of said cylinder. In practice, these elastic fingers are made solid with the platform, the bottom of said platform being cut out in such a manner that the fingers can be turned up to the desired position.

The glass cylinder being supported by the platform E, encloses the sieve F, and when the flame is burning, a powerful and uniform current of air passes up from below and enters the flame at the inner and also at the outer side of the cone, so that a perfect combustion is effected, and a brilliant and powerful flame is produced.

The cone G is connected to the air-sieve F by a hinge-joint, or in any other suitable manner, and it is provided with inwardly-projecting lips, e , at the end of its slot, f , as seen in fig. 1 of the drawing. The current of air passing up from below impinges against these lips, and is thrown into the flame, so that the flame spreads, and produces a powerful and brilliant light.

By forcing these lips in more or less, the width of the flame can be increased or diminished, and if the lips are forced in a little too far, the flame spreads to such an extent that it strikes the inner surface of the glass cylinder.

By these means a lamp-burner is obtained which effects a perfect combustion of the oil, and produces a brilliant light; and, furthermore, if a small portion of the vapors should escape unconsumed, the oil resulting from the condensation thereof accumulates in the cup B, whence it flows back into the cistern, and the outside of said cistern always remains clean and free from moisture; whereas, with the burners of the ordinary construction, it will be found that the cistern becomes moist and soiled with oil on its external surface, such oil being the result of the condensation of unconsumed vapors, which condensation takes place on the outside of the burner, whence the oil runs down and spreads on the cistern.

Having thus described our invention, what we claim as new, and desire to secure by Letters Patent, is—

The construction and arrangement of the cup B, recessed thimble D, supporting-sleeve e, open platform E, air-sieve F, and cone G, as and for the purpose described.

CHARLES WEBER,
HENRY REIMANN.
